(57) **CLAIM**

I claim the ornamental design for a boot, as shown and described.

DESCRIPTION

FIG. 1 is a perspective view of a boot showing my new design;

FIG. 2 is a left side elevation view thereof;

FIG. 3 is a right side elevation view thereof;

FIG. 4 is a front elevation view thereof;

FIG. 5 is a rear elevation view thereof; and,

FIG. 6 is a top plan view thereof.

The broken lines are for illustrative purposes only and form no part of the claimed design.

1 Claim, 5 Drawing SheetsFIG.1.

FIG. 2.

FIG. 3.

FIG.4.

FIG.5.

FIG.6.
